US00D774539S

(12) **United States Design Patent** (10) **Patent No.:** **US D774,539 S**
He et al. (45) **Date of Patent:** **** Dec. 20, 2016**

(54) **DISPLAY SCREEN WITH GRAPHICAL USER INTERFACE**

(71) Applicant: **INBAY TECHNOLOGIES INC.**,
Kanata (CA)

(72) Inventors: **Mingxuan He**, Ottawa (CA); **Xiaoxi Pang**, Ottawa (CA); **Randy Kuang**, Ottawa (CA); **Robert Frank Steklasa**, Ottawa (CA); **Stanislus Kisito Xavier**, Ottawa (CA)

(73) Assignee: **INBAY TECHNOLOGIES INC.**,
Ottawa (CA)

(**) Term: **14 Years**

(21) Appl. No.: **29/489,133**

(22) Filed: **Apr. 28, 2014**

(51) LOC (10) Cl. **14-04**

(52) U.S. Cl.

USPC **D14/487**; D14/490

(58) **Field of Classification Search**

USPC D14/485-488, 346; D18/4.4, 7; 704/4
CPC .. H04L 63/083; H04L 9/3213; G06Q 20/4012

(57) **CLAIM**

The ornamental design for display screen with graphical user interface, as shown and described.

DESCRIPTION

FIG. 1 is a front view of a display screen with graphical user interface, showing the new design.

The broken lines illustrating an electronic device and the display screen are included for the purpose of illustrating portions of the article and do not form part of the design.

1 Claim, 1 Drawing Sheet
